OF

O 14,956

No. 14,956 Apr. 8, 1884

UNITED STATES PATENT OFFICE.

GEORGE W. SWETT, OF LANSINGBURG, ASSIGNOR TO SWETT, QUIMBY & CO., OF TROY, NEW YORK.

DESIGN FOR AN OIL-STOVE.

SPECIFICATION forming part of Design No. 14,956, dated April 8, 1884.

Application filed December 17, 1883. Term of patent 7 years.

To all whom it may concern:

Be it known that I, GEORGE W. SWETT, of the village of Lansingburg, county of Rensselaer and State of New York, have invented and 5 produced a new and useful Improvement in Ornamental Designs for Oil or Wick Stoves, of which the following is a specification.

My invention relates to the form of the parts composing and as they are arranged to produce a design for the side and front of an oil-stove as the same is shown to be produced in the annexed engraving, forming a part of this specification.

The form of the parts composing the design 15 shown as produced in the annexed engraving is designated by letter reference, and such form is described as follows:

The letter T indicates the top, which is horizontally placed, is rectilinear in form, and 20 has a beveled edge arranged to overhang the sides and front.

The letter A designates the sides of the stove-body proper, both of which are alike, and there is produced on each of them centrally the bordered panel a^2 , and above and below the latter a row of connected rings, a^3 , formed in relief on the said sides.

The letter a^2 indicates a beveled band-molding on the sides, immediately below the overhang of the top.

The letter B designates the base of the stove, having a beveled edge, and this base in its rearward extension subtends the sides of the stove-body proper beyond its rear end, 35 E, to the same extent as does the stove-top.

The letter P designates a post arranged between the extension of the top and base, at the corners of the latter, so that the design of the sides of the stove as thus produced by the sub-40 tension of the top and base, the corner-posts as arranged, and the exterior form of the body part of the stove at the sides is a design distinctive in its character, and it would convey the same impression to an observer whether 45 its individual features were combined with the design for a stove-front, as shown, or some other design for an oil-stove front was used.

The design for the front of an oil-stove, as

shown, is produced by the central pilaster, F^2 , and the two corner pilasters, $F^3 F^4$, which vertically divide the area of the front in two recessed panels, $F^5 F^6$, the doors $D D$, each of which has three mica lights or panes, with arched tops, the two upper hearths, $H^1 H^1$, and the major hearth H^2 , below the upper hearths. 55

The design for the more prominent features of an oil-stove front produced by the upper hearths and the major lower hearth would give character and identity to the design, whether the doors employed in the stove above 60 the said hearths were formed as shown or differently produced; hence I do not limit my invention of a design as produced for the lower part of an oil-stove front by the arrangement of the said hearths, as shown, to their combination with features of design employed on the upper part of the oil-stove front.

Having thus described my design, what I claim, and desire to secure by Letters Patent, is—

1. The design for an oil-stove, consisting of the central pilaster, F^2 , and the corner pilasters, $F^3 F^4$, which vertically divide the front in two recessed panels, $F^5 F^6$, the doors $D D$, each having mica panes or lights that are 75 arched at the tops, the two upper hearths, $H^1 H^1$, and the major lower hearth, H^2 , as shown and described.

2. In a design for an oil-stove, the front section consisting of the two upper hearths, H^1 , 80 H^1 , and the major lower hearth, H^2 , as shown and described.

3. The design for an oil-stove, consisting of the sides of the body part and their exterior, the subtending edges of the top and base beyond the body part, and posts between the top and base at the corners of their rearward extension, as shown and described.

Signed at Troy, New York, this 6th day of December, 1883, and in our presence, whose 90 names, as witnesses, were by us hereto written.

GEORGE W. SWETT.

In presence of—

THOS. S. SPRAGUE,
CHARLES S. BRINTNALL.
